UNITED STATES PATENT OFFICE.

EDWARD HUBER, OF MARION, OHIO.

TRACTION-ENGINE.

SPECIFICATION forming part of Letters Patent No. 271,464, dated January 30, 1883.

Application filed January 3, 1882. (No model.)

To all whom it may concern:

Be it known that I, EDWARD HUBER, of Marion, in the county of Marion, and in the State of Ohio, have invented certain new and useful Improvements in Traction-Engines; and I do hereby declare that the following is a full, clear, and exact description thereof, reference being had to the accompanying drawings, and to the letters of reference marked thereon, making a part of this specification.

My invention relates to certain special improvements in traction or road engines, and has especial reference to the three following points or features, viz: first, to constructing the gearing which communicates rotary motion to the driving-wheels in such manner that it will be compensating; secondly, to producing peculiar means whereby said gearing may be instantly rendered non-compensating; 2 and, thirdly, to constructing the peripheries of the driving and supporting wheels in such manner as to make them operate successfully on both hard and soft ground, and to prevent lateral slipping when traveling on hill-sides, or 25 roads inclining from the center to the sides, each of which several features will be herein-after more specifically pointed out.

In the accompanying drawings, which make a part of this specification, like letters of reference are employed to designate corresponding parts, and in which Figure 1 represents a plan view of my improved traction or road engine; Fig. 2, a side elevation of the same; Fig. 3, a like view of the driving gear-wheel and the 35 several devices which co-operate immediately therewith; Fig. 4, a sectional view taken longitudinally through the main driving-shaft and the several gear-wheels which together constitute my improved compensating-gear; Fig. 5, 40 a transverse sectional view taken through the rim of one of the main driving-wheels, showing the relative thickness of the peripheral ribs or projections, to be more fully pointed out hereinafter; and Fig. 6, a similar view through 45 the rim of one of the front wheels, showing the relative diameters of the periphery thereof.

The letter A designates the main driving gear-wheel, which is of ordinary construction, and which is fitted on the rear axle or shaft of 50 the traction-engine, and is adapted to freely rotate thereon.

Rigidly secured to the hub of one of the driving-wheels, or made integral therewith, is an auxiliary gear-wheel, B. Said gear is located in close proximity to the main driving gear-wheel above alluded to, and rotates with the driving-wheel, to the hub of which it is secured. 55

The letter C refers to another or an auxiliary gear-wheel of larger diameter than the gear-wheel B, and which is provided with a hub or lateral boss, C', the said gear being rigidly secured or keyed to the rear axle of the engine. Journaled to the main driving gear-wheel near its periphery, and at approximately diametrical points, are two systems of pinions, 65 D and E, each of which systems is composed of three pinions, E', E² and E³, and D' D² D³, respectively. The pinions D' and D³ of the system D are secured to one shaft, and the pinions E' and E³ of the system E are also secured to one shaft. The pinions D² and E² are 70 respectively provided with a shaft.

The letters Y Y indicate two yokes or brackets secured to the main driving-gear A, forming journals for the outer ends of the shafts 75 of the pinions above referred to, the body of the main driving-gear forming the opposite journals for the said shafts.

It will be observed by referring to Fig. 2 of the drawings that the pinions D² and E² both 80 intergear with the gear B, and respectively with the pinions D' and E', and the pinions D³ and E³, which are secured respectively to the same shafts as the pinions last above mentioned, intergear both with the gear C, thus 85 resulting in a geared connection of the main driving-wheel G, which, as has heretofore been mentioned, is free to revolve on the rear axle independently of the rotation of said axle and of the main driving-wheel G', which is rigidly 90 secured to the said rear axle with the main driving gear-wheel A. Thus it will also be observed that the geared connection existing between the said main driving gear-wheel A and the main driving-wheels G and G' is mechanically different, this difference resulting 95 from the difference or inequality in the diameter of the auxiliary gear-wheels B and C. Therefore when rotary motion is imparted to the main driving-gear A by means of suitable 100 gearing interposed between it and the engine-shaft, and its said gear-wheel A in turn im-

- parts rotation to the driving-wheels G and G' , the power exerted is greater on the one than on the other wheel, the difference in power resulting from the difference in the diameter of the auxiliary gears B and C , before alluded to. This result may be obtained by a slight modification of this part of my invention, such modification consisting in making the gears B and C of equal diameter and the pinions of unequal diameters—that is to say, making the pinions designated by the letters D^3 and E^3 of a diameter which, though corresponding as between themselves, yet differs from that of the pinions D and E or D' and E' .
- In the traction-engines in which the axle revolves there is greater resistance to the main driving-wheel secured to the axle than to the one which loosely revolves independently of the axle, this inequality in resistance resulting from the fact that the weight of the engine is on the axle, and the friction caused by such weight forms the source of resistance. The difference in the power exerted on the respective main driving-wheels by reason of the difference in the diameters of the auxiliary gear-wheels compensates for the inequality of the resistance to said driving-wheels, and practically renders the power which each driving-wheel receives from the main driving gear-wheel the same, the resistance caused by the friction above alluded to consuming the extra power which one wheel would otherwise receive, thus, it will be observed, resulting in a perfect balance or distribution of the power originally exerted for propelling my engine or an engine having my improved gear applied thereto; and, on the other hand, the two driving-wheels being independent of each other in turning or rounding curves, the one traveling in the longer arc is free to revolve more rapidly than the other, thus avoiding all twisting and distorting tendency to the engine.
- The second part of my invention relates to a device for rendering the compensating-gear above described non-compensating, the object being to prevent the undue slipping of either of the main driving-wheels in passing over slippery or soft ground. It consists of providing the pinions D^3 and E^3 with flanges, lugs, or projections I , which extend beyond the peripheries thereof, and of supplying the hub C' with an annulus, H , grooved on its circumference and adapted to receive a second annulus, H' , whose inner periphery is provided with an annular flange, which fits into the groove above mentioned, the said flange and groove serving to keep the one annulus in place on the other, and yet permitting of their independent movement. To the annulus H is secured a suitable yoke, K , which passes through guides K' , fixed to the frame. Interposed between the said yoke and the fixed guide, or otherwise suitably arranged, is a spring, which serves to keep the annuli H and H' out of the line of travel of the flanges I , and to a convenient part of the yoke is also

flexibly connected a lever, L , by means of which the above-mentioned annuli are advanced from their normal position.

From the foregoing it will be observed that when the engine is passing over soft or slippery ground, and either driving-wheel is found to slip or rotate independently of the other, they may be instantly locked together by advancing the annuli H H' laterally until the latter engages the flanges I on the pinions D^3 and E^3 , preventing their further rotation, and that consequently of the other pinions around their respective axes, resulting in practically uniting the main driving gear-wheel A positively with the driving-wheels G and G' , and thus causing a union of rotation.

That part of my invention hereinbefore designated as the "first" and "second" parts, it will be observed, may be applied to any other purpose than a traction-engine.

The third part of my invention appertains to the peculiar construction of the peripheries of the driving and supporting wheels; and it consists in making the outer surface of the rims of the front wheels, M , of two diameters, the larger serving to prevent lateral slipping by reason of its sinking into the ground, and the smaller serving to support the weight and ride over the soil, which is rendered more solid by reason of the lateral displacement effected by the sinking of the larger diameter of the rim into the earth. On hard roads the larger periphery forms the supporting-surface of the rim, and, being slightly narrower than the remaining part of the rim, it acts as an ordinary narrow-faced rim where there is no tendency to sink. The peripheries of the driving-wheels are similarly constructed to those of the front wheels, with the addition of a series of raised projections, d e , those on the larger diameter being broad and shallow and those on the smaller diameter being narrower and thicker. The broad shallow projections d serve to prevent the wheels from slipping while passing over hard or macadamized or plank roads or bridges, and being broad, they cause the engine to ride smoothly. The narrower and thicker projections on the smaller diameter serve to take into softer ground, and form an additional safeguard or resistance against slipping, and acting, as they do, in the more solid portions of the ground, (caused as above described,) they form, in connection with the non-compensating device, (by which the driving-wheels are locked together,) a perfect and reliable means of preventing the independent or joint slipping of the drivers, and effectively overcome the practical difficulties heretofore experienced in this particular in the use of traction-engines. The openings in the smaller diameter (indicated by the letter f) are to allow the mud to pass through and prevent the clogging or filling up of the spaces between the projections e . These openings may be cut between any number of the projections.

Having described my invention, what I

claim, and desire to secure by Letters Patent, is—

1. The combination, in a compensating-gear, of a loosely-mounted main driving gear-wheel having diametrically-disposed systems of gears journaled thereto near its periphery, each system consisting of two intermeshing pinions on one side and a single pinion on the other, with a gear-wheel made integral with the driving-wheel and meshing with one pinion of each system on one side thereof, and a gear-wheel fixed to the axle and meshing with both pinions on the opposite side of the driving-gear, substantially as shown and described.
- 15 2. The combination of the flanges, their pinions D³ and E³, with the annuli, and means for shifting the same and producing the non-compensating gear, substantially as described.
3. For a traction-engine, a main driving-

wheel, the rim thereof composed of two diameters having transverse ribs or projections, and openings through that portion of the rim of smallest diameter, substantially as described.

4. A wheel for traction-engines having the periphery of its rim of unequal diameter, the larger circumference being provided with spaced projections of a broad, flat form, and the smaller diameter with spaced projections of a narrower and thicker form, substantially as shown and described.

In testimony whereof I affix my signature, in presence of two witnesses, this 7th day of December, 1881.

EDWARD HUBER.
